UNITED STATES PATENT OFFICE.

CARL A. FLOOD, OF FRAMINGHAM, MASSACHUSETTS, ASSIGNOR TO DENNISON MANUFACTURING COMPANY, OF FRAMINGHAM, MASSACHUSETTS, A CORPORATION OF MASSACHUSETTS.

PROCESS OF MANUFACTURING SHEET ARTICLES.

Application filed December 20, 1926. Serial No. 155,804.

This invention relates to the production of shipping tags or the like, which are characterized by having string-receiving openings that are reinforced by patches or washers.

The present invention discloses means whereby patches may be continuously cut from a sheet or strip of patch material, preferably being first divided into longitudinal 10 ribbons having interfitting marginal undulations, these ribbons in turn being guided to the opposite faces of a strip of tag stock and individual patches being separated from the strips and applied to opposite surfaces of 15 the stock at desired intervals. Either subsequently to or simultaneously with the application of the patches to the tag, holes are punched through the patches and the tag to receive the string. Preferably the patch is 20 adhesively secured to the tag, the patch material being previously coated with a substance which is rendered adhesive when wet and the longitudinal ribbons passing through a suitable factor for wetting the 25 same, the patches being so located upon the tags that the protuberant undulatory marginal portions thereof are located at either side of the string-receiving openings in order to provide a sufficient amount of reinforcing 30 material about the same. The individual patches are preferably severed from the longitudinal strip or ribbon along a straight edge which is in substantial alignment with the edge of the tag stock, whereby the patch 35 as applied to the tag may have its edge in substantial registration with the edge of the tag and the entire area between the string-receiving opening and the adjoining edge of the tag may be reinforced by patch material. 40 The above and further objects of the invention will become apparent to those skilled in the art upon a reading of the subjoined description and claims in conjunction with the accompanying drawings, which illustrate 45 one form of apparatus for performing the desired series of operations.

In the drawings,

Fig. 1 is a side elevational view of the apparatus;

Fig. 2 is an end elevational view of the same, with parts broken away and parts shown in section;

Fig. 3 is an elevational side view of the

patch feed mechanism and the die which cooperates therewith;

Fig. 4 is a top view of similar mechanism;

Fig. 5 is a detailed elevational view;

Fig. 6 is an elevational view of the die assembly;

Fig. 7 is a section on line 6—6 of Fig. 5 showing the die members mutually approached;

Fig. 8 is a similar view showing the same spaced apart; and

Fig. 9 is a plan view of a portion of the patch stock, the dot and dash lines showing the way the separate patches are cut from the same.

While the accompanying drawings illustrate one form of apparatus which is adapted continuously to receive strips of patch material and tag stock to form the patches and to apply the same to the tags while forming string-receiving openings in the superimposed patches and tags, it is to be understood that this concrete embodiment of the apparatus is merely shown for purposes of illustration and the steps, and operations occurring in conjunction with this method and apparatus need not exactly coincide with the illustrated method nor occur continuously as shown.

Referring more particularly to Figs. 1 and 2, the patch stock 7, which is preferably gummed, may be received in a continuous strip from the reel 1, passing under and over suitable guide members 3 and 2 respectively to a cutter of the type having disks with wavy or zig-zag edges, indicated by the numeral 4, and comprising a series of disks 90 with undulated peripheries adapted to rotate in close juxtaposition to a plain roller in order to cut the strip of patch material into longitudinal ribbons, edge portions of which are provided with undulations which are adapted substantially to interfit. The ribbons as thus cut are directed in any suitable manner to a moistening factor 10 which is adapted to render the gum or mucilaginous substance upon one surface of the ribbon 100 readily adhesive.

The ribbon is then drawn to the guide element 13 which is adapted to guide one strip of ribbon in a path above and parallel to the path of the other strip, the lower strip 105 being twisted so that its moistened face is

turned upwardly. For example, referring more particularly to Figs. 3 and 4 for an understanding of this part of the process and the corresponding apparatus, it is to be understood that the guiding mechanism 13 comprises superimposed plates having channels 14, designated by dotted lines (Fig. 3), which are adapted to receive the ribbons of patch material above each other.

- 10 Preferably the patch ribbons are moved in synchronized relation with the movement of the tag stock itself, this movement being imparted by means of a shaft 20 having suitable eccentrics 21, 22 and 23 for driving 15 various parts of the mechanism in synchronized relation. As shown, the eccentric 22 may be connected by suitable linkage to the lever 27 which is adapted to reciprocate the patch-feeding mechanism through link 28. 20 This patch feeding mechanism preferably comprises a frame 39 slideable on guide element 13 and having oppositely disposed diagonal fingers 29, juxtaposed ends of which are shaped to engage the undulated marginal 25 portions of the patch ribbon and which are normally drawn towards each other by a spring 30. Reciprocation of the feeding mechanism results in the pinching of the margins of the ribbon by the ends of the 30 fingers 29 and reciprocating movement of these fingers results in feeding of the patch material toward the die. In order to hold the patch material in advanced position in the manner indicated, suitable retention fingers 33, which correspond somewhat in dimensions and relation to each other with the arrangement of members 29 (Fig. 5), are supported upon the members 13, being 35 drawn toward each other by spring 32. 40 Any suitable guides 31 may extend from this portion of the mechanism towards the die assembly indicated in general by numeral 40. Thus the ribbon is advanced by fingers 29 which grip the same, but fingers 45 33 engage re-entrant marginal portions of the strip to retain it in advanced position, being forced into more firm gripping relation with the same by tendency of the strip to move backward when the motion of 50 carrier 13 and fingers 29 is reversed, while retraction of the member 39 and the angularity of fingers 29 cause them to be spread apart and the spring 30 to be expanded by the cam-like bearing of the former upon the curved marginal surfaces of the patch 55 ribbon.

The die assembly preferably comprises upper and lower die elements 41 and 42 respectively (Figs. 4 and 5) and an intermediate fixed guide piece 38 with related parts. Preferably this guide piece is provided with suitable slots for receiving the parallel ribbons of patch stock, as designated by numeral 63, and is provided with 60 suitable slots 34 for guiding the tag stock 50

in a plane parallel to and spaced between the planes of the patch ribbons. Above the plane of slots 34 is the die member 41 which is adapted to have an edge 62 pass downwardly in close alignment with the edge of 70 the tag stock while die 42 has a similar upward movement. The plate 37 projects from the mid portion of bracket 60 and is adapted to cooperate with the dies to sever or shear the individual patches from the patch strips. The die 41 is also provided with an intermediate plunger 43, which may be projected below the plane of the rest of the upper die. Preferably the die elements are operated by the eccentric mechanism 75 previously referred to through suitable connecting rods 45 and 47 respectively (Fig. 2), while the plunger is actuated through cam 23, being provided with a spring 57 normally to hold it up.

The die elements are thus preferably brought into juxtaposed relation, being spaced apart at a distance (Fig. 7) which will permit their plane surfaces to press the patches into adhesive engagement with the tag without objectionally crushing the same, while the plunger 43 is driven downward for a sufficient distance to cut small disks out of the superimposed patches and tags, these disks dropping from the machine through the bore 49 in the lower die. Thus between each step-by-step movement, flat adjoining surfaces of the die elements are adapted to press a gummed patch upon each of the opposite faces of a tag element, subsequently to the severing of the individual patches from the ribbons of patch material, and concomitantly with the cutting of the string-receiving openings in patch and tag material. Subsequently the individual tags may be separated from the tag stock in any suitable manner.

If desired, the original strip or sheet of patch material may be wider than shown and a sufficient number of patch ribbons 110 may be cut by a single cutter having an appropriate number of disks to supply several patch-applying machines; it being understood that in case the patch stock is slit in the same continuous operation with the application of the patches to the tags as shown for illustration, the cutter is driven at a speed proportional to that of the main shaft 20 by any suitable means.

It is thus evident that a continuous 120 method of making tags with adhesively affixed reinforcing patches for the string-receiving holes is possible by the arrangement illustrated herein, the method of cutting the patches from a longitudinal strip 125 of material permitting economy in the use of the patch stock which is generally of high quality and rather expensive material; at the same time the cutting and application of the patches to the tag may be accom- 130

plished in a single operation and in synchronized relation with the cutting of the longitudinal ribbons so that production of tags of this type may take place with high efficiency and at nominal cost.

I claim:

1. The method of making tags of sheet material with an opening reinforced by patches, which comprises cutting the patch material into longitudinal strips, subsequently feeding one of said strips to a position above and another of said strips to a position below a strip of tag stock, cutting off individual patches, and simultaneously 15 punching openings therein and in the tag stock located therebetween and applying the patches to the tag stock, and subsequently separating individual tags from the strip of tag stock.
- 20 2. The method of making tags of sheet material with an opening reinforced by patches, which comprises feeding a strip of patch material in intermittent synchronism with a strip of tag stock, cutting the patch material in two longitudinal strips, guiding one of said strip to a position above and the other of said strips to a position below the stock, cutting off individual patches, and applying the patches to the tag stock, and subsequently 25 separating individual tags from the strip of tag stock.
3. The method of making tags of sheet material with an opening reinforced by patches, which comprises cutting two longitudinal strips from the patch material with margins having alternate recesses and protuberances of like but reverse contour, the protuberances of one strip fitting the recesses of the next strip, subsequently feeding one 35 of said strips to a position above and the other of said strips to a position below the stock, cutting off individual patches, concomitantly punching openings therein and in the tag stock located therebetween and applying the patches to the tag stock, and subsequently 40 separating individual tags from the strip of tag stock.
4. The method of making tags of sheet material with an opening reinforced by patches, which comprises cutting the patch material into longitudinal strips with margins having alternate recesses and protuberances of like but reverse contour, the protuberances of one strip fitting the recesses of the next strip, guiding one of said strips to a position in juxtaposed parallelism to the tag stock, and transversely severing the strips at intervals corresponding to the sum of one recess and one protuberance 45 to provide individual patches, applying the patches to the tag stock, and punching openings therein and in the tag stock.
- 60 5. The method of making tags of sheet material with an opening reinforced by patches, which comprises cutting the patch

material into longitudinal strips with undulated margins, protuberances of one of which substantially interfit with recesses of the other, feeding similar strips thus formed to a position above and below a strip of tag 70 stock with the protuberances in substantially registering relation, severing individual patches from the strip and punching a hole through said patches and said tag therebetween.

6. The method of making tags of sheet material with an opening reinforced by patches, which comprises cutting the patch material into longitudinal strips with undulated margins, protuberances of one of 80 which substantially interfit with recesses of the other, feeding similar strips thus formed to a position above and below a strip of tag stock with the protuberances in substantially registering relation, severing patches 85 from the patch strips along a line substantially even with the edge of the tag stock and applying the individual patches to the tag stock.

7. The method of making tags of sheet 90 material with an opening reinforced by patches, which comprises cutting the patch material into longitudinal strips with undulated margins, protuberances of one of which substantially interfit with recesses of 95 the other, feeding similar strips thus formed to a position above and below a strip of tag stock with protuberances in substantially registering relation, severing the patches from the strip at a point adjoining the edge 100 of the tag stock, pressing the patches and tag stock into adhesive engagement, and punching a hole through said patches and said tag therebetween.

8. The method of making tags of sheet 105 material with an opening reinforced by patches, which comprises cutting the patch material into longitudinal strips with undulated margins, protuberances of one of which substantially interfit with recesses of 110 the adjoining strip, feeding similar strips thus formed in intermittent synchronism with a strip of tag stock, effecting the step-by-step movement of said patch strips in such a manner that each step is for a distance substantially equal to the sum of a recessed and protuberant portion of a margin of the strip, and concomitantly effecting the step-by-step movement of the tag stock so that each stepped movement thereof is synchronized with a similar movement of the patch strips so that the latter are brought to a position above and below the tag stock with protuberances in substantially registering relation, pressing the patches into adhesive engagement with the tag stock, and punching a hole through said patches and said stock therebetween.

9. The method of making reinforcing patches for tags which comprises longitudi-

nally cutting a sheet of reinforcing material into strips whose margins have alternate recesses and protuberances of like but reverse contour, the protuberances of each strip substantially fitting the recesses of the next adjacent strips, and then transversely severing the strips, whereby the sheet is cut longitudinally and transversely into patches with substantially no waste of stock.

10 10. The method of making reinforcing patches for tags which comprises longitudinally cutting a sheet of reinforcing material into strips whose margins have alternate recesses and protuberances of like but reverse contour, the protuberances of each strip substantially fitting the recesses of the next adjacent strips, and then transversely severing the strips at staggered points, whereby the sheet is cut longitudinally and transversely into patches with substantially no waste of stock.

11. The method of making reinforcing patches for tags which comprises longitudinally cutting a sheet of reinforcing material into strips whose margins have alternate recesses and protuberances of like but reverse contour, the protuberances of each strip substantially fitting the recesses of the next adjacent strips, and then transversely severing the strips at staggered points, whereby the sheet is cut longitudinally and transversely into patches with substantially no waste of stock.

12. The method of making tags of sheet material with openings reinforced by patches, which comprises cutting a patch strip with successive marginal undulations, subsequently feeding the patch strip to a cutting element by means of elements engaging the undulations, thereupon cutting separate patches from the end of the strip and applying the same to the tag stock.

13. The method of making tags of sheet material with openings reinforced by patches, which comprises cutting a patch strip with successive marginal undulations, subsequently engaging successive protuberant portions of the patch strip and thus feeding the same by a step-by-step movement to a cutting element, thereupon cutting separate patches from the end of the strip and applying the same to the tag stock.

Signed by me at Framingham, Massachusetts, this 9th day of December, 1926.

CARL A. FLOOD.
